UNITED STATES PATENT OFFICE.

GUSTAV H. SCHMIDT, OF BYDGOSZCZ, POLAND.

SOFT COLLAR AND STIFFENER.

Application filed December 8, 1923. Serial No. 679,401.

To all whom it may concern:

Be it known that I, GUSTAV H. SCHMIDT, a citizen of the United States, residing at Bydgoszcz, in the county of Bydgoszcz,

5 Poland, have invented certain new and useful Improvements in Soft Collars and Stiffeners; and I do hereby declare the following to be a full, clear, and exact description of the invention, such as will enable others skilled in the art to which it appertains to

10 make and use the same.

The invention has relation to soft shirt collars and has for its object to stiffen the same whereby to retain the predetermined 15 shape when worn so as to present a neat and tidy appearance and admit of the stiffener being readily detached when the collar is to be laundered and quickly replaced after the collar has been laundered and otherwise 20 in condition to be worn.

Other objects and advantages will be apparent and suggest themselves as the nature of the invention is understood.

While the drawings illustrate an embodiment 25 of the invention it is to be understood that in adapting the same to meet different conditions and requirements, various changes in the form, proportion and minor details of construction may be resorted to without departing from the nature of the invention.

Referring to the accompanying drawings forming a part of the application:

Figure 1 is a perspective view of a soft shirt collar and stiffening means therefor embodying the invention, parts being broken away,

Figure 2 is a diagrammatic view of the collar and stiffener,

Figure 3 is a detail view showing the ends 40 of the collar and stiffener and the necktie, and

Figure 4 is a detail view.

Corresponding and like parts are referred to in the following description and designated in the several views of the drawings by like reference characters.

The collar illustrated is of the type commercially designated as soft as it is not starched or similarly stiffened and is of the 50 folding or turndown pattern and may be of any design or constructed of fabric of any nature not intended to be starched. The collar comprises the front 1 and back or neckband 2, the latter having terminal extensions forming tabs in which are provided buttonholes 3 to receive the usual

collar button. If preferred, the front 1 may be provided at its ends with buttonholes to receive buttons applied to the front of the shirt, whereby to secure the points of the 60 collar after the necktie has been placed in position. In accordance with the present invention, pockets 4 are provided at the ends of the neckband or back 2 and these pockets are closed at their top, bottom and 65 outer edges and are open at their inner ends. A stiffener 5 of cardboard or other suitable sheet material is provided and is preferably of an outline to correspond to the configuration of the neckband or back 2 and is disposed to lie between the front 1 and part 2 with its ends inserted in the pockets 4. 5^a indicates an eyelet in the stiffener 5 intermediate its ends, and 5^b other eyelets adjacent each end, said eyelets alining with the 75 button holes in the collar neckband when the stiffener is in place, and adapted to receive the shanks of collar buttons to assist in holding the stiffener in proper relationship with the collar. This stiffener maintains the 80 shape of the collar when worn and may be easily removed when the collar is to be laundered and quickly placed in position after the collar has been laundered and is otherwise in condition to be worn. A hook 85 6 and companion eye 7 are applied to opposite ends of the stiffener and serve to secure the same and prevent detachment of the collar therefrom. In addition to the hook and eye, other eyes 8 are applied to end 90 portions of the stiffener and are designed to receive hooks 9 applied to the ends of a necktie 10, whereby to hold the latter in place when formed into a bow, thereby obviating the necessity of passing the necktie around 95 the collar and tying the same which frequently causes inconvenience and trouble.

What is claimed is:

A folding or turndown soft collar having 100 pockets at opposite ends of the neckband, a stiffener insertable between the folds of the collar and having its ends inserted in the said pockets, and complemental fastening means applied to corresponding ends of the stiffener and to a necktie to retain the latter 105 in place.

In testimony whereof I affix my signature in presence of two witnesses.

GUSTAV H. SCHMIDT.

Witnesses:

HENRIK ZOCHAVIAWESNIY,
RUDOF OSTERMIICNIY.
